Application July 18, 1949, Serial No. 3,985

Term of patent 14 years

(Cl. D13—1)

To all whom it may concern:

Be it known that we, Charles Pumilia, Jr., and Frank Jurisich, Jr., citizens of the United States of America, residing at New Orleans, in the State of Louisiana, have invented a new, original, and ornamental Design for Service Stations, of which the following is a specification, reference being made to the accompanying drawing, forming a part hereof.

Fig. 1 is a top plan view of a service station, showing my new design.

Figure 2 is a side elevational view.

Figure 3 is an end elevational view.

We claim:

The ornamental design for a service station, as shown.

CHARLES PUMILIA, JR.
FRANK JURISICH, JR.
